DESIGN FOR A COMBINED SLIPPER AND SOCK

William Sherman, New York, N. Y.

Application February 10, 1943, Serial No. 109,520

Term of patent 7 years

To all whom it may concern:

Be it known that I, William Sherman, a citizen of the United States of America, residing in New York city, county of New York, and State of New York, have invented a new, original, and ornamental Design for a Combined Slipper and Sock, of which the following is a specification, reference being had to the accompanying drawing, forming part thereof,

The figure on the drawing is a perspective view of a combined slipper and sock showing my new design. The opposite side has substantially the same appearance as the side shown.

I claim:

The ornamental design for a combined slipper and sock, substantially as shown and described.

WILLIAM SHERMAN.
